REFRIGERATOR CAR CONSTRUCTION

Victor E. West, New Kensington, Pa., assignor
to Standard Railway Refrigerator Company,
Chicago, Ill., a corporation of Delaware

Application April 28, 1939, Serial No. 270,500

17 Claims. (Cl. 62—17)

My invention relates to insulated refrigerator cars used to transport perishable commodities, such as vegetables, fruits, berries, meats, eggs, frozen fish, etc. It is particularly related to that class of refrigerator car commonly known as the "top bunker" type.

One of the objects of my invention is to provide a refrigerant container that is easy to install and easy to remove when repairs or replacement is necessary.

Another object is to provide means for the unobstructed circulation of air around the container.

Another is to provide means to support the container and hold it in place in the car.

Another is to provide a plurality of beams from which lading such as dressed meat can be conveniently suspended.

Another is to provide supporting means for the insulating materials in the roof of the car.

In the drawings:

Fig. 1 shows a typical cross section through a refrigerator car incorporating my improved construction.

Fig. 2 is a section taken longitudinally of the car on line 2—2 of Fig. 1.

Fig. 3 is a sectional view taken on the line 3—3 in Fig. 1 to show the arrangement of container supports and carlines.

Fig. 4 is an enlarged view of a portion of Fig. 1.

Fig. 5 is a plan view of Fig. 4. The insulated partition is not shown in order to more clearly show the detail of the carline.

Fig. 6 is a section taken on line 6—6 in Fig. 4.

Fig. 7 is an enlarged view of a portion of Fig. 1.

Fig. 8 is an enlarged view of a portion of Fig. 1.

My invention is adaptable to a refrigerator car having spaced apart walls 2, an insulated roof 3, an insulated floor 4, a foraminous floor or floor rack 5 above the insulated floor, and an air space 6 between said floors.

A refrigerant container 8 is positioned subjacent the roof 3 and adjacent a wall 2. A hatch opening 9 is provided preferably in the roof of the car above the refrigerant container 8 for filling it with a refrigerant, removing the refrigerant or cleaning the container. The hatch opening 9 may be provided with the usual plug, lid, locking and supporting mechanisms. A drain having a closing valve may also be provided for the container.

Under certain conditions frost will form on the bottom 10 of container 8. To prevent melted frost from dripping onto the lading, an insulated partition 11 provided with a

drip pan 12 is positioned below and spaced from the container. The space 13 between the container bottom 10 and the partition 11 forms a flue so that air may circulate therethrough and be cooled by contact with the chilled container bottom 10.

To support the container 8 above the partition 11 metallic spools 14 and 34 are provided. These spools are arranged in spaced relationship to each other and have their upper ends 15 secured to the container bottom 10. In the drawings I have shown the spools 14 and 34 secured to the container bottom by welding but any other suitable means may be used. The lower ends 16 of the spools 14 and 34 are adapted to rest upon the 15 drip pan 12 of partition 11.

To support the partition 11 I provide carlines 17 upon which the partition rests. These carlines 17 extend transversely of the car and have their ends 18 secured to the car walls 2—2. With the above described construction the entire weight of the refrigerant container 8, the refrigerant within the container, and the partition 11 is carried by the carlines 17.

In the preferred form of my improvement the spools 14 are arranged with respect to the carlines 17 so that each spool is positioned directly above a carline, it being understood that more than one spool may be positioned above an individual carline. This arrangement is shown in Fig. 3 of the drawings.

From the drawings it is evident that with my improved construction no separate ceiling is required to support the roof insulating materials 23. The top 24 of container 8 will support that portion of the insulation above it, ridge members 25 spanning the space 26 between and supported by the containers 8—8 support the insulation above the space 26, transverse metallic sheet members 27 span the spaces 28 between the ends 40 of adjacent containers 8—8 and support the insulation thereabove. At the eaves I provide the sheet metal members 29 to support the roof insulation.

To prevent the refrigerant container 8 from shifting due to service movements of the car a plurality of depending studs or dowel pins 19 protruding below the roof 3 are provided. The studs 19 are rigidly secured to the roof structure preferably to a member such as a roof carline 20 by welding or other suitable means. The sides 21 of the container 8 are provided with outwardly extending flanges 22 having holes of suitable size arranged and positioned so as to engage the studs 19 when the container 8 is in position.

Another means for preventing shifting of the refrigerant container is provided by securing an upwardly extending metallic member 30 to the top of a carline 17; this may be accomplished by

- 5 any suitable means but I prefer to weld member 30 to carline 17. Member 30 is positioned on the carline 17 so that when container 8 having a spool 34 is assembled in the car with partition 11 and carline 17 the member 30 will extend through a hole 31 provided in partition 11 and enter the hollow spool 34 engaging the inside of the wall 32 thereof.
- 10

I have also found it desirable to tie the container 8, the partition 11 and the carline 17 together by some readily releasable means. For this purpose a depending bolt 33, having its upper end 35 anchored within a hollow spool 34 and its shank 36 extending through the member 30 so that its lower end 37 extends through a hole 38 in carline 17 and is adapted to receive a nut 39 or other suitable securing means, is provided.

In the conventional refrigerator car used for transporting meats, a meat rack positioned near the roof and extending over the lading space is generally provided. Such a rack generally consists of beams extending transversely of the car between the walls in combination with and supporting rods or rails spaced on fixed centers and extending lengthwise of the car above the lading space.

With my improved construction a meat rack is not necessary as I propose to utilize the carlines 17 from which to hang a lading such as is generally suspended from a meat rack. In the preferred form of my improved refrigerator car construction the carlines 17 are of an inverted U section having the depending sides 40 of the U terminating in outwardly and upwardly extending flanges 41 of uniform width throughout the entire length of the carline. For attaching or suspending a lading I provide the members 42 having their central portions shaped to suitably engage with the conventional type of meat hook 43 and their ends 44 rebent so as to engage the flanges 41 of carline 17 when the member 42 is in an operative position. A predetermined number of the members 42 may be placed on each carline by sliding them on before the carline is positioned in the car. After the carline 17 is assembled together with the other elements of the car superstructure the members 42 are theft proof as they can be disengaged only by sliding them off an end of the carline. The slideable feature described above is an advantage over the fixed spacing of the longitudinally extending members of the conventional meat rack as the attaching members 42 automatically space themselves according to the size of the package suspended therefrom.

To simplify the installation of the carlines 17 I provide the longitudinally extending members 51 suitably spaced above and parallel to the car floor 4. These members 51 preferably each have a vertically extending leg 52 which I secure to the car wall 2 and a portion 53 extending horizontally toward the interior of the car to form a shelf 54. In the drawings (see Figs. 1 and 4) I have shown an angle; however, this member could be a T section or a Z section. I cut away a part of the horizontally extending portion 53 leaving a gap 55 in the shelf 54, said gap in length being slightly greater than the width of the carline 17 adjacent the end thereof. In the preferred construction a member 51 extending sub-

stantially the full length of the car is provided for each of the opposite walls 2-2, each of said members having a plurality of spaced apart gaps 55, said gaps being spaced to bring them under the ends of the carlines 17 when assembled. Relatively short members 56 having their ends 57 adapted to rest on the shelf 54 with their central portions 58 spanning the gaps 55 are provided to support the ends of the carlines 17. The members 56 preferably are secured to both the longitudinally extending members 51 and the carlines 17 after assembly in the car. Carlines installed as described above are easily put in place or removed without disturbing the car wall structure. 5 10 15

To provide a circulatory system whereby the air cooled by the refrigerant may enter the lading space and the air warmed by the lading may enter the cooling chamber I provide in or near the walls 2-2 a vertical duct 43 extending from near the floor 4 to near the roof 3, said duct having its upper portion 44 communicating with the space 13 between container bottom 10 and partition 11 and having its lower portion communicating with the space 6 between the floor 4 and the rack 5. The vertical duct 43 is separated from the lading space by the insulated partition 50.

The insulated partition 11 is preferably inclined outwardly and downwardly so that air cooled and densified by the refrigerant will move by gravity toward and into the vertical duct 43.

The insulated partitions 11 on opposite sides of the car are spaced apart to provide an air passageway 45 adjacent the longitudinal center 35 of the car through which the warm air rises and moves into the refrigerant chambers on opposite sides of the car. The inclined partitions 11 direct the air warmed by the lading into and through the passageway 45. 40

The margins of the inclined partitions 11 adjacent the passageway 45 may be provided with insulated members 46 extending upwardly therefrom so as to further raise the bottom of the air entrance ports into the refrigerant chamber 45 above the lower portion of the inclined partition 11 so as to cooperate with the inclined partition to direct the movement of circulation of air. These members 46 are spaced away from the refrigerant containers to provide flues 47 therebetween. 50

The insulated partition 11 below the container 8 and the insulated partition 50 between the side wall 2 and the lading space are associated to form a continuous uninterrupted insulation from the passageway 45 to the foraminous floor 5. The space 13 below the refrigerant container 8 and the duct 43 between the insulated partition 50 and the wall 2 are associated and arranged to provide a continuous uninterrupted air flue for circulating air from the passageway 45 to the space 6 below the foraminous floor 5 so that heat from the lading space cannot be absorbed by the cold air circulating until the air has reached the space below the foraminous floor. Therefore air warmed by the lading will rise upwardly and be guided by the inclined partition 11 into the passageway 45 and enter the refrigerating chamber where it will be cooled and densified by the refrigerant in container 8 and therefore will descend through flue 47 and move downwardly along the inclined partition 11 until it reaches the vertical wall duct 43 which it descends by gravity into the space 6 below the foraminous

floor 5 from whence it rises to replace the aforesaid warmed air.

The accompanying drawings illustrate the preferred form of the invention, though it is to be understood that the invention is not limited to the exact details of construction shown and described, as it is obvious that various modifications thereof, within the scope of the claims, will occur to persons skilled in the art.

10 I claim:

1. In a refrigerator car having spaced apart insulated car walls, an insulated roof, an insulated floor, a foraminous floor above the insulated floor, an air space between said floors, in combination with a refrigerant container positioned under the roof and adjacent a wall, supporting means for said container, said means comprising a plurality of metallic spools having their upper ends secured to the bottom of said container and their lower ends resting on an insulated partition spaced from the bottom of said container so as to provide a flue therebetween for the circulation of air under said container.

25 2. In a refrigerator car having spaced apart insulated car walls, an insulated roof, an insulated floor, a foraminous floor above the insulated floor, an air space between said floors, and a duct associated with a wall extending substantially from top to bottom of said wall, the lower portion of said duct communicating with said air space in combination with a refrigerant container positioned under the roof and adjacent said wall, supporting means for said container, said means comprising a plurality of metallic spools having their upper ends secured to the bottom of said container and their lower ends resting on an insulated partition spaced from the bottom of said container so as to provide a flue therebetween for the circulation of air under said container, communicating means between said flue and said duct, said partition being inclined outwardly and downwardly toward a wall so that air cooled and densified by the refrigerant in said container will move by gravity toward and into said duct through which it descends by gravity and enters the space between said floors.

40 3. In a refrigerator car having spaced apart insulated car walls, an insulated roof, an insulated floor, a foraminous floor above the insulated floor, an air space between said floors in combination with a refrigerant container positioned under the roof and adjacent a wall, supporting means for said container, said means comprising a plurality of metallic spools having their upper ends secured to the bottom of said container and their lower ends resting on an insulated partition spaced from the bottom of said container so as to provide a flue therebetween for the circulation of air under said container, carlines extending between and secured to said walls, the tops of said carlines engaging the underside of said partition so as to support the combined weight of said partition, said container and the refrigerant therein.

45 4. In a refrigerator car having spaced apart insulated car walls, an insulated roof, an insulated floor, a foraminous floor above the insulated floor, an air space between said floors in combination with a refrigerant container positioned under the roof and adjacent a wall, supporting means for said container, said means comprising a plurality of metallic spools having their upper ends secured to the bottom of said

5 container and their lower ends resting on an insulated partition spaced from the bottom of said container so as to provide a flue therebetween for the circulation of air under said container, carlines extending between and secured to said walls, the tops of said carlines engaging the underside of said partition so as to support the combined weight of said partition, said container and the refrigerant therein, said spools being arranged and associated so that some of the 10 spools are directly above and aligned with one of said carlines.

5. In a refrigerator car having spaced apart insulated car walls, an insulated roof, an insulated floor, a foraminous floor above the insulated floor, an air space between said floors in combination with a refrigerant container positioned under the roof and adjacent a wall, supporting means for said container, said means comprising a plurality of metallic spools having 20 their upper ends secured to the bottom of said container and their lower ends resting on an insulated partition spaced from the bottom of said container so as to provide a flue therebetween for the circulation of air under said container, inverted U shaped carlines extending between and secured to said walls, the tops of said carlines engaging the underside of said partition so as to support the combined weight of said 25 partition and said container, the depending sides 30 of said U shaped carlines terminating in parallel flanges of uniform width extending outwardly and upwardly, a plurality of members positioned under said carlines in transverse relation thereto, said members having rebent ends 35 adapted to slidably engage said flanges so as to provide means for suspending a lading from said carlines.

6. Means to restrain the container described in claim 1 from shifting laterally due to service 40 movements of the car, said means consisting of a plurality of depending studs secured to the roof and protruding from the underside thereof and flanges extending outwardly from the top edges 45 of the sides and ends of the container, said flanges having a plurality of holes therein, said holes being arranged to engage said studs when the container is positioned in the car.

7. Means to restrain the container described in claim 4 from shifting laterally due to service 50 movements of the car, said means consisting of one of the spools of claim 4 being hollow and positioned over a hole extending through said partition and a member secured to the top of said carline, said member being adapted to extend through said hole and engage said spool.

8. Means to restrain the container described in claim 4 from shifting laterally due to service 60 movements of the car, said means consisting of one of the spools of claim 4 being hollow and positioned over a hole extending through said partition, a hollow member secured to the top of said carline, said member being adapted to extend through said hole and enter said spool and securing means adapted to extend through said hollow member whereby said spool is connected to said carline and secured with relation thereto.

9. Means to support the carline described in claim 3, said means consisting of a metallic 70 member positioned lengthwise of the car, above and parallel to said floor and adjacent a side wall, said member having a vertical leg secured to said wall and a horizontal portion extending away from said wall to form a shelf, a section of 75

- said horizontal portion cut out to form a gap in said shelf, a second metallic member spanning said gap and having its ends resting on said shelf, said second member forming a seat for the ends of said carline.
10. Means to support the carline described in claim 3, said means consisting of a metallic member positioned lengthwise of the car, above and parallel to said floor and adjacent a side wall, said member having a vertical leg secured to said wall and a horizontal portion extending away from said wall to form a shelf, a section of said horizontal portion cut out to form a gap in said shelf, a second metallic member spanning said gap and having its ends resting on said shelf, said second member forming a seat for the ends of said carline, and means to secure said second member to said shelf and said carline respectively.
15. 11. In a refrigerator car as described in claim 3 and having a plurality of spaced apart refrigerant containers, metallic sheet members spanning the spaces between and supported by said containers, said containers and said members engaging the underside of said roof to support the insulating material thereof.
20. 12. In a refrigerator car as described in claim 3 and having a plurality of spaced apart refrigerant containers, metallic sheet members spanning the spaces between and supported by said containers, said members having upwardly embossed portions engaging the insulating material of the roof to help hold it in place.
25. 13. In a refrigerator car having spaced apart walls, a vertical duct associated with one of said walls, a refrigerant container below the roof and adjacent said wall, a partition below said container in spaced relation thereto to provide a flue which communicates with the upper part of said duct, means to support said container on said partition, and means to support said partition, said first mentioned means comprising spools disposed between said container and said partition.
30. 14. In a refrigerator car having spaced apart walls, a vertical duct associated with one of said walls, a refrigerant container below the roof and adjacent said wall, a partition below said container in spaced relation thereto to provide a flue which communicates with the upper part of said duct, means to support said container on said partition, and means to support said partition, said first mentioned means comprising spools disposed between said container and said partition.
35. 15. In a refrigerator car having spaced apart walls, a vertical duct associated with one of said walls, a refrigerant container below the roof and adjacent said wall, a partition below said container in spaced relation thereto to provide a flue which communicates with the upper part of said duct, means to support said container on said partition, and means to support said partition, said first mentioned means comprising spools disposed between said container and said partition.
40. 16. In a refrigerator car having spaced apart walls, a vertical duct associated with one of said walls, a refrigerant container below the roof and adjacent said wall, a partition below said container in spaced relation thereto to provide a flue which communicates with the upper part of said duct, means to support said container on said partition, and means to support said partition, said first mentioned means comprising spools disposed between said container and said partition.
45. 17. In a refrigerator car having spaced apart walls, a refrigerant container below the roof and adjacent one of said walls, a partition below said container in spaced relation thereto, means to support said container on said partition, and means to support said partition, said last mentioned means comprising spools disposed between said container and said partition.

VICTOR E. WEST.
